(57) **CLAIM**

The ornamental design for a concrete form clip, as shown and described.

DESCRIPTION

FIG. 1 is a top front right perspective view of a concrete form clip in accordance with my new design;

FIG. 2 is a top plan view thereof;

FIG. 3 is a front elevation view thereof;

FIG. 4 is a right side elevation view thereof, the left side elevation view being a mirror image to the right side elevation view;

FIG. 5 is a top front right perspective view of another embodiment of a concrete form clip in accordance with my new design;

FIG. 6 is a top plan view thereof;

FIG. 7 is a front elevation view thereof; and,

FIG. 8 is a right side elevation view thereof, the left side elevation view being a mirror image to the right side elevation view.

The broken lines show portions of the concrete form clip that form no part of the claimed design.
